JOHN H. DEAL, OF HORNELLSVILLE, NEW YORK.

Letters Patent No. 66,954, dated July 23, 1867.

IMPROVEMENT IN STEPS FOR SPRING-WAGONS.

The Schedule referred to in these Letters Patent and making part of the same.

TO ALL WHOM IT MAY CONCERN:

Be it known that I, JOHN H. DEAL, of Hornellsville, Steuben county, in the State of New York, have invented a new and useful Improvement in the Construction and Application of Steps to Platform-Spring Wagons; and the following is a full, clear, and exact description of the same, reference being had to the accompanying drawings, making a part of this specification, in which—

Figure 1 represents a perspective view of a double right-angle connecting-joint link for platform springs, with the step on the top.

Figure 2 shows the top of the step.

The object of my invention is to attach a step to the joint of platform springs, which is the most convenient and desirable place for mounting the wagon.

My invention consists in having the right-angle connecting-joint link elevated sufficiently above the bolt to which the top spring is attached, and supporting on it a roughened disk of any desired size, so as to answer the purpose of a step for mounting into the wagon, or for taking out boxes or bales in delivering parcels by express-men and wagoners.

My right-angle link iron A is constructed in a similar manner to those in use for connecting the ends of platform springs together by the bolts B B'. The upper portion of the iron A extends over the opening and bolt B', and is joined together at the top, forming a flat surface, on which the plate or disk C is firmly secured by riveting it to the iron A. The step or disk C may be of any desired size or form, the upper surface being roughened, so as to prevent the foot from slipping off as a person mounts the wagon.

It will readily be seen that there is no place so convenient and desirable for placing a permanent step to a platform-spring wagon as the one above described.

What I claim as new and useful, and desire to secure by Letters Patent, is—

Placing and securing a plate or disk, to form a step, on the iron or connecting-link of platform springs, for express or other wagons, substantially in the manner herein described, for the purposes set forth.

In testimony whereof I hereunto subscribe my name this   day of   , 1867, in the presence of—

JOHN H. DEAL.
